United States Patent Office

Des. 208,588
Patented Sept. 12, 1967

208,588

SHIPPING BOX OR SIMILAR ARTICLE

Arthur E. Hanson, Laurens, Iowa 50554

Filed Aug. 25, 1965, Ser. No. 86,706

Term of patent 3½ years

(Cl. D58—12.6)

FIGURE 1 is a perspective view of a shipping box or similar article, showing my new design;

FIGURE 2 is a top plan view thereof on a reduced scale;

FIGURE 3 is a side elevation thereof, both side elevations being the same;

FIGURE 4 is a bottom plan view thereof; and

FIGURE 5 is an elevational view of the end opposite that shown in FIGURE 1.

The characteristic features of my design reside in a rectangular box having a divided top with a plurality of circular shaped holes arranged in a single row thereon, the longer sides having a series of vertically positioned elongated apertures, the end panels being provided with a single horizontally placed aperture, and having two elongated parallel apertures running on the longitudinal axis of the bottom thereof, all as shown.

I claim:

The ornamental design for a shipping box or similar article, substantially as shown and described.
